United States Patent Office.

THOMAS S. DISSTON, OF PHILADELPHIA, PENNSYLVANIA, ASSIGNOR TO
HENRY DISSTON, OF SAME PLACE.

Letters Patent No. 73,880, dated January 28, 1868.

IMPROVEMENT IN SAW-GUMMING MACHINE.

The Schedule referred to in these Letters Patent and making part of the same.

TO ALL WHOM IT MAY CONCERN:

Be it known that I, THOMAS S. DISSTON, of Philadelphia, Pennsylvania, have invented an improved Saw-Gumming Machine; and I do hereby declare the following to be a full, clear, and exact description of the same.

My invention consists of certain mechanism, fully described hereafter, for rapidly and accurately cutting the fronts of saw-teeth.

In order to enable others familiar with machinery of this class to make and use my invention, I will now proceed to describe its construction and operation, reference being had to the accompanying drawing, which forms a part of this specification, and in which—

Figure 1 is a sectional elevation of my improved saw-gumming machine, showing the same applied to a circular saw.

Figure 2, a side elevation.

Figure 3, a transverse sectional view on the line 1-2, fig. 1.

Figure 4, a sectional plan view on the line 3-4, fig. 1, and

Figure 5 a plan view.

Similar letters refer to similar parts throughout the several views.

The cast-iron frame A of the machine consists of two end parts, a and a', connected together by and forming a part of the curved guides b and b', in which a frame, B, is arranged to slide, as shown in the drawing, and in each of the guides b' are formed two recesses or grooves t for a purpose described hereafter, (see figs. 1 and 3.) A feed-screw, C, provided with jam-nuts d d' and a hand-wheel, d', passes through the rear end of the frame A, and the inner end of the said screw bears against a spring, g, and is so attached to the sliding frame B that the latter is caused to travel back or forth on the guides b and b' when the hand-wheel d' is turned. A horizontal spindle, D, passes through and turns in the sliding frame B, and has at each end a crank-handle, h, and a pinion, i, upon the said spindle, gears into a cog-wheel, j, on a spindle, E, which also turns in the sliding frame. Owing to the flanges or shrouds on the cog-wheel j, the latter always remains in gear with the pinion, but both spindles D and E can be moved longitudinally in their bearings for a purpose described hereafter, and to the latter spindle, and within the frame B, is secured a cutter-wheel, F. An adjustable guide-bar, G, having a slot, l, is attached to the upper inclined portion of the frame A by a nut, m, upon a set-screw, m', the latter, together with other set-screws r r, entering a narrow longitudinal groove, p, formed in the under part of the frame A, for a purpose described hereafter.

The points of the teeth of a circular saw are generally sharpened by hand with an ordinary file. When this has been repeated several times, it becomes necessary, in order to impart proper shape to the tooth, to cut away the semicircular front of the same—an operation which my improved saw-gummer is designed to perform. In the portion of a saw, X, shown in red lines, fig. 1, but three teeth are represented, y, y¹, and y², in cutting which the tooth y is the first operated on, after which it will be necessary to cut each tooth in succession, moving the instrument around the saw in the direction of the arrow 1. The sliding frame B and cutter F are moved towards the rear end of the frame A by operating the hand-wheel d', and the machine is then applied to the saw-blade X. The latter enters the groove p, and the machine is raised or lowered on the saw by operating the set-screw m' until the cutter F is brought in contact with the semicircular portion of the tooth y, after which the set-screws r are turned, and the machine firmly secured to the saw.

The next operation is to rotate the cutter-wheel F, to which motion is communicated, through the gearing described, by turning the handles h h. At the same time the cutter is fed up against the front of the tooth by turning the screw-rod C, and this is continued until the tooth y has been cut to the desired depth. The next stage of the operation is to stop the motion of the cutter-wheel, and to move up the jam-nuts d until they are in contact with the rear of the frame A, which will effectually stop all forward motion of the screw or cutter-wheel beyond this point in operating on other teeth. The length of the cut on the tooth y having been now determined, the screw-rod, its jam-nuts, and the sliding frame, are moved back. In fig. 1, the tooth y is supposed to have been thus cut away from the point shown by the dotted line x, and it will be seen that the jam-nuts d, on the screw-rod, have been moved back from the rear of the frame A, to a distance equal to the depth of this cut. The set-

screws ν are now loosened, and the machine moved until its cutter-wheel is brought in contact with the inner portion of the tooth y^1 , in which position it is secured, as before described. The guide-bar G is then adjusted until its outer end bears against the sharpened tooth y , when it is secured by its nut, m , as shown in fig. 1. The machine is now operated as before, and the tooth y^1 cut away until the forward motion of the cutter is arrested by the jam-nuts d coming in contact with the rear of the frame. The sliding frame is then drawn back, the machine removed, and applied to the third tooth y^2 , the guide-bar G bearing against the tooth y^1 , and determining the position of the frame A on the saw. The tooth y^2 is cut in the same manner as the preceding ones, and the operation is repeated on each tooth of the saw until they have all been cut, when the machine is removed, and the points of the teeth are dressed to the proper degree of sharpness with an ordinary file, or otherwise. It will be seen that the guide-bar G serves, with a cut tooth, as a gauge to determine the proper position of the machine in adjusting the same for operating accurately on another tooth. The spring g , against which the feed-screw bears when pushing up the sliding frame, acts as a cushion, and prevents any tendency which the cutter might have to become jammed against the tooth when pushed up suddenly. The face of the cutter-wheel F is considerably wider than the edge of the saw, so that as the former becomes dull it may be moved laterally, the arrangement of the spindles, as before described, permitting such adjustment. It will be seen, on reference to fig. 3, that, after the removal of the handle h and cog-wheel j , the frame B, when brought to a position opposite the recesses t of the guides b' , may be moved laterally, and detached from the frame of the machine. It will also be seen, on reference to fig. 1, that the curve of the guides b and b' approximates in form to that of the curve of the saw, and that the sliding frame and cutter-wheel must necessarily follow the same curve.

I claim as my invention, and desire to secure by Letters Patent—

1. The frame A, with its curved guides, b and b' , in combination with the adjustable frame B and its cutter F sliding on the said guides, and carrying a cutter, F.

2. The adjustable guide-bar G, combined with the frame of the machine, substantially as and for the purpose specified.

3. The jam-nut or nuts d , in combination with the screw C, for adjusting the frame B, substantially as described.

4. The recesses t on the guides b' of the frame A, constructed as described, when the said recesses are arranged in respect to the sliding frame B, for the admission of the latter to and its withdrawal from the said frame A, as set forth.

In testimony whereof, I have signed my name to this specification in the presence of two subscribing witnesses.

THOMAS S. DISSTON.
